(57) **CLAIM**

The ornamental design of a shoe sole with interchangeable members, as shown and described.

DESCRIPTION

FIG. 1 is a perspective view of a shoe sole with interchangeable members showing my new design;

FIG. 2 is a first side view thereof;

FIG. 3 is second side view thereof;

FIG. 4 is a front view thereof;

FIG. 5 is a rear view thereof;

FIG. 6 is a top view thereof; and,

FIG. 7 is a bottom view thereof.

(Continued)

See application file for complete search history.

The broken lines in the figures are included for the purpose of illustrating portions of a shoe sole with interchangeable members or environmental subject matter and form no part of the claimed design.

1 Claim, 5 Drawing Sheets
